UNITED STATES PATENT OFFICE.

RICHARD PETERSON, OF PHILADELPHIA, PENNSYLVANIA.

DESIGN FOR A PANEL FOR A STOVE-PLATE.

SPECIFICATION forming part of **Design No. 12,511**, dated **October 4, 1881.**

Application filed January 10, 1881. Term of patent 14 years.

To all whom it may concern:

Be it known that I, RICHARD PETERSON, a citizen of the United States, residing in Philadelphia, Pennsylvania, have invented or produced a new and original Design for a Panel for a Stove-Plate, of which the following is a specification.

My design for a panel for a stove-plate is fully represented in and by the accompanying drawing *a a* being the opposite parallel edges of the panel, and *b b* the rounded upper and lower edges of the same. The central and prominent figure of the panel is the representation, *A*, of a basket filled with coals. There are *15* two ornaments, *B B'*, one above and the other below the central figure, the character of these

ornaments being too clearly illustrated to need description.

I claim—

The design for a stove-panel, said design *20* comprising the central figure, *A*, representing a basket filled with coal, and the upper and lower ornaments, *B B'*, substantially as shown and described.

In testimony whereof I have signed my name *25* to this specification in the presence of two subscribing witnesses.

RICHARD PETERSON.
